UNITED STATES PATENT OFFICE.

THOMAS P. CONLON, OF NEW YORK, N. Y.

LOCK, BOLT, OR CATCH FOR DOORS, WINDOWS, SHUTTERS, OR THE LIKE.

1,347,251.

Specification of Letters Patent.

Patented July 20, 1920.

Application filed October 25, 1915. Serial No. 57,783.

To all whom it may concern:

Be it known that I, THOMAS P. CONLON, a citizen of the United States of America, residing in the borough of the Bronx, city of New York, county of the Bronx, State of New York, have invented a new and useful Lock, Bolt, or Catch for Doors, Windows, Shutters, or the like.

The present invention relates to improved locks or catches for doors, windows, shutters and the like, and particularly a lock, catch or bolt, which will automatically become positively deadlocked upon the closing of the door, so as to prevent any person from opening the same from the outside, unless they have the means of operating by key or otherwise, what corresponds to the handle in the accompanying drawings.

The object of my invention is to provide a snap lock combined with a dead lock, working automatically upon the closing of the door, window or shutter, and being deadlocked when shut, the deadlock being also automatically disengaged when the handle or other opening means is actuated to open the lock, bolt or catch, and not otherwise, the deadlock release being actuated by the slight jar occurring when the door, window or shutter is closed.

Another object of the invention is to provide such a device which may be readily incorporated in any of the well known forms of locks and which in a simplified form will be particularly adapted for catches for dumb-waiter doors and for doors to fire exits, and in all cases where it is desirable to have a lock, or catch which may be readily opened from the inner side but which will be positively deadlocked, automatically when the door is shut, so that the bolt of the lock or catch cannot be forced back, until the opening device is actuated.

With these and other objects in view my invention is shown in the accompanying drawings, and will be hereinafter fully described with reference thereto and finally pointed out in the claims.

In the accompanying drawings, Figure 1 is a vertical sectional view of my improved device; Fig. 2 is a similar view showing the position of the parts before the door is closed again, having been once opened; Fig. 3 is a perspective view of the foregoing from the underside thereof; Fig. 4 is a sectional view with parts broken away of a slightly modified form of construction; Fig. 5 is a vertical

sectional view of a further modified form of construction; Fig. 6 is a plan sectional view of the last form. Fig. 7 is a perspective view of a still further modified form and Fig. 8 is a detail of one of the parts thereof.

Similar reference characters indicate corresponding parts throughout the several figures of the drawings.

Referring to the drawings and more particularly to Fig. 1 thereof in which my invention is introduced in a latch such as is generally used on dumbwaiter doors, the housing or casing 10 is provided at the foremost portion thereof with a contracted portion 11, in which is provided a squared opening 12, a bolt 13 is provided in the said casing, the forward end of which is beveled so as to slide into an opening to fit it on the door jamb and be caught by the nose 14. The shaft 15 of the said bolt engages an opening 16 of the casing. As lever handle 17 is pivoted to the casing at 18 and extends out of an opening 19 thereof, the tongue 20 of the lever extends into the casing and engages at 21 its forward end a cut out portion 21 of the bolt, the very tip of the said tongue being in very close proximity to the yoke member 25. A spring 22 is provided on the shaft 15 to press the bolt outward. A notch 23 is provided on the bolt a short distance from the yoke member 25, the said yoke member 25 being pivoted to the casing and held in engagement with the bolt by the spring 26. The following points must be noted in regard to the relative position of the parts in this figure, namely, the action of the tongue 20 is to force the yoke 25 away from the bolt, and this action is further helped by the face of the yoke 25 being at an angle to the direction of the pivoted motion of the tongue. The operation is as follows, the tongue 20 moves the yoke 25 downward sufficiently so that the yoke member 25 will not engage in the notch 23. The tongue not being actuated the yoke 25 would engage in the notch 23. When the tongue 20 is actuated through movement of the handle 17 to withdraw the bolt from the keeper, the end of the tongue first depresses the yoke member out of engagement with the notch 23, releasing the bolt and permitting the door to be opened.

On the return movement of the tongue 20 it engages and is held with the yoke member 25 and the bolt 13 is prevented from finishing its forward movement until such time as the door is shut against the jam of the said door

and then the slight jar occasioned by the said shutting causes the yoke to release the tongue 20. However before the yoke 25 releases the tongue 20, the bolt 13 can be 5 pressed backward and will act the same as a simple snap bolt and allow the door to easily close, but when the slight jar of the closing allows the parts to return to the position as illustrated in Fig. 1 the bolt will then be 10 deadlocked and cannot be forced back by any instrument inserted between the door and the jamb.

It will be noted that in the forms shown in Figs. 1, 2 and 3 no actual jar is necessary 15 in order to spring the bolt fully out to the position shown in Fig. 1, from the position shown in Fig. 2, when the bolt is repressed by the keeper for the reason that if the bolt 13 be pressed backward, the tongue 20 remaining in the position shown in Fig. 2, when the pressure on the bolt is quickly released as it would be in passing into the jamb of the door, the bolt will quickly jump 20 forward and strike sharply against the tongue 20, causing it to be released by the yoke 25, and the bolt will return to the locked position shown in Fig. 1. This action will not however occur when the handle 17 is used to retract the bolt for the reason that 30 the tongue 20 returning with the bolt 13 impedes this action.

In Fig. 4, I have shown a slightly modified form of carrying out my invention, in which I provide a lever 27 perpendicularly disposed in normal position thereof, and engaging the slot in the bolt 28, which operates through the opening of the casing 31. A yoke member 29 engages a notch 30 in the upper surface of the bolt in the full thrown 40 position thereof, and a cam surface is provided at the inner side of the lever 27, which when the said lever is operated to retract the bolt, lifts the yoke 29 out of engagement with the notch 30 and thereby removes the 45 deadlocking effect of the said yoke when the bolt is retracted. The bolt is temporarily arrested and prevented from full protraction before the yoke member 29 engages the notch 30, by means of a lug 33 provided on 50 the upper surface of the bolt, having a beveled face 34 which engages the beveled corner 35 of the casing 31, a spring 32 being provided on the under side of the bolt which causes the engagement of the said beveled 55 surfaces. In this way the bolt is free to move when the same engages the keeper during closing of the door, but when the bolt is within the keeper, the shock of the contact of the door with the door jamb causes 60 the disengagement of the notch 33 from the beveled corner 35 of the casing, and the bolt is thereupon projected to its full locking position, the yoke engaging the notch and deadlocking the bolt.

65 In the form of construction shown in Figs.

5 and 6, my invention is embodied in a door lock of the form operated by the turning of a handle on the inside and by a key from the outside. The bolt 36 is retracted and thrown by the turning of a shaft 37 which is connected thereto by levers 38 and 39, pivoted at 40 and connected to a slot 41 provided in a lug 42 formed on the bolt. In projected position of the bolt, a member 43 pivoted to the casing at 44 supported by a link 45 from the pivot point 40 of the levers 38 and 39 engages a notch 46 on the bolt, thereby forming a deadlock. Another notch 47 is provided on the side of the bolt farthest from the outside of the door, and a weighted member 48 is pivoted to a standard 49, and is held in engagement with the underside of the said bolt by reason of a spring 50.

In operation the turning of the shaft 37 moves the bolt inwardly and causes the pivot point 40 to be lowered thereby disengaging the member 43 from the notch 46. When the knob is released the bolt is caught by the engagement of the weighted member 48 with the notch 47, before the member 43 deadlocks the same by engagement with the notch 46, and the bolt is yieldable and may be closed easily. The impact of the door with the frame, in closing however disengages the member 48 from the notch 47, and the bolt therefore becomes deadlocked by engagement of the member 43 with the notch 46.

In the modified form illustrated in Figs. 7 and 8, my invention is embodied in a form 100 of lock in which the lock proper 50 arranged on the door is provided with recesses 52 and 53, which engage projections 54 and 55 of a plate 56 secured to the door frame. Holes 57 are provided in the projections 54 and 55 105 which are engaged by locking member 58, shaped as indicated in Fig. 8, and provided within the lock 50. These locking members are operated by levers 59 pivoted at 60 and 61, and moved downwardly by a bar 62 110 which may be operated in any suitable manner. In order to prevent the deadlocking of the bolt before the closing of the door a catch device is employed, comprising a weighted member 65 pivoted at 66, which 115 engages a notch 67 of the bar 62, when the lock is operated. This is disengaged by the impact of the door when closing.

It will be noted that when the hand is released from the lock after opening the door, it releases the handle or knob as the case may be gradually, that is it does not permit the full force of the spring of the bolt to come into effect, so that the bolt is held from its full return movement by engagement of the end of the tongue with the yoke in the first form of my invention, or by engagement of the lug 33, second form, and by engagement of the weighted lever 48, in the last form. When the end of the 130

bolt further engages the keeper, the deadlocking yoke not being in locking position permits the bolt to be forced back tensioning its spring. When the bolt is within the 5 keeper this spring forces it outwardly and as there is no retarding effect upon the spring, as when the handle or notch is held by the hand, the full force of the spring comes into effect, and the momentum of the 10 bolt caused thereby, is sufficient to fully project the bolt, causing the same to ride across the means for preventing its full return movement. It will therefore be seen that the means for preventing full return 15 movement of the bolt does not come into effect when the spring of the bolt is permitted to exert its full driving force. This only occurs when the bolt is fully retracted and released without the least retaining effect 20 thereon, and if the hand is held on the handle for only a fraction of its movement, the means for preventing full return movement of the bolt will operate. The shock of compact or jar when closing the door 25 therefore, is not essential to the positive deadlocking of the device, but will make its successful operation a certainty, and where the spring is of insufficient strength to overcome the effect of the means for preventing 30 full return movement of the bolt, the shock of impact will alone be responsible for the releasing of the bolt and the deadlocking of the device.

My invention can be employed in many 35 forms of locking devices, and I will have it understood that I can apply it to all forms of snap locks, where a deadlock is also desired, and that changes in the form, position, size, or functions of the parts from 40 those disclosed will not change the principle or sacrifice any of the advantages of my invention, and that it will not make any vital change in the advantages of the said invention either to have the impact of the 45 door against the jamb operate the deadlock setting mechanism, solely by itself, or to have the same operated and released by the sharp spring forward of the bolt when the nose of the same passes over the jamb of 50 the door or the catch provided thereon, so,

Having thus described my invention, what is claimed and what is desired to be secured by Letters Patent is:—

1. In a locking device, a casing, a spring 55 bolt in said casing provided with a nose adapted to project from said casing, means for retracting the bolt within said casing, means adapted to deadlock said bolt in the fully projected position thereof, said means 60 for retracting said bolt adapted to disengage said deadlocking means, means adapted

to prevent full projected movement of said bolt after retraction and adapted to hold said bolt out of engaging position with said deadlocking means, said last named means 65 adapted to be disengaged by shock of impact to permit full thrust movement of said bolt and engagement therewith of said deadlocking means.

2. In a locking device, a casing, a spring 70 bolt in said casing provided with a nose adapted to project from said casing and having a cut out portion, an independent manual lever pivoted within said casing and provided with a handle projecting outward 75 therefrom and with a nose engaging said cut out portion to retract said bolt, means adapted to deadlock said bolt in the fully projected position thereof, said lever being adapted to disengage said deadlocking 80 means from said bolt during retraction.

3. In a locking device, a casing, a spring bolt provided with a notch therein, means adapted to engage said notch in fully projected position of said bolt to deadlock the 85 same, means for retracting said bolt, said retracting means adapted to disengage said deadlocking means from said notch to permit full retraction of said bolt, and means adapted to prevent full return movement 90 of said bolt, said last named means adapted to be made inoperative by shock of impact to permit full return movement of said bolt, and engagement of said deadlocking means with said notch. 95

4. In a locking device, a casing, a bolt provided with a notch therein, a spring on said bolt, a spring pressed yoke member adapted to engage said notch in fully projected position of said bolt to deadlock the 100 same, a handle provided with a lever, said lever engaging said bolt and adapted to retract the same against the force of said spring, said lever being provided with means for disengaging said yoke member from said 105 notch to permit full retraction of said bolt, means adapted to prevent full return movement of said bolt, said last named means having a holding effect non-resistant to the full projecting strength of said spring, said 110 last named means adapted to be made inoperative by the shock of impact to permit full return movement of said bolt and engagement of said yoke with said notch.

In testimony that I claim the foregoing 115 as my invention, I have signed my name in presence of two subscribing witnesses.

THOMAS P. CONLON.
